(57) **CLAIM**

The ornamental design for a business form with self laminating wristband and labels, as shown and described.

DESCRIPTION

FIG. 1 is a plain view of a first embodiment of a business form with self laminating wristband and labels showing our new design; and,

FIG. 2 is a plain view of a second embodiment for the business form with self laminating wristband and labels including special precautions labels.

The broken line showing of portions of the business form is included for the purpose of illustrating environmental structure and forms no part of the claimed design.
